THOMAS B. WICKHAM, OF GRANVILLE, OHIO.

Letters Patent No. 82,668, dated September 29, 1868.

IMPROVEMENT IN FARM-GATES.

The Schedule referred to in these Letters Patent and making part of the same.

TO ALL WHOM IT MAY CONCERN:

Be it known that I, THOMAS B. WICKHAM, of Granville, county of Licking, State of Ohio, have invented a new and useful Improvement upon Farm-Gates; and I do hereby declare that the following is a full and exact description thereof, reference being had to the accompanying drawings, and to the letters of reference marked thereon.

The nature of my invention consists in constructing a sliding gate, so arranged that it can be held either open or closed, without the use of latches or buttons, a gate that can be manufactured at a small expense, and when properly adjusted cannot sag down in either direction.

The letters A B C respectively represent the three posts of my gate, of which the post A is slotted, as shown on Figure 2, and it has also a small brace at its bottom, marked *a*, adjusted as thereon shown.

The post B has attached to it a trundle, *b*, and a clutch, *c*, each adjusted in the manner and at the points represented.

The post C is mortised out at the point *d*, and the guide-slat D is fastened therein, as represented.

This guide-slat connects the posts B and C midway, or thereabouts, between the tops and bottoms of the same. The end of this slat fastened to post C is bevelled upward, as shown, for the purpose of giving aid in holding the gate securely open, when it is desirable so to do.

My gate proper is marked E on the drawings. It is made in the usual form of sliding gates, except that its middle slat is extended beyond the others, and constitutes an arm, marked *g*. This arm has a trundle-head attached thereto, marked *f*, and a trundle, *h*.

My gate is operated as follows, namely:

To close it, the operator slides it on the trundle *b*. The front end passes up the brace *a*, into the slotted post A. The gate now rests principally on said brace, and there is no need of latch or button to hold it shut.

To open the gate, I slide it backward, until the trundle *h* passes upward on the bevelled end of guide-slat D. The weight of the gate is now in great part transferred to the trundle *h*, which passes beyond said bevel, and holds the gate securely open.

The clutch *c*, arm *g*, the two trundles and guide-slat, arranged and combined in the manner shown, serve to keep the gate in line, and render permanent sagging in either direction almost impossible.

What I claim as my invention, and desire to secure by Letters Patent, is—

A farm-gate, having posts A, B, and C, brace *a*, clutch *c*, trundles *b* and *h*, gate E, arm *g*, and guide-slat D, constructed, arranged, and operating substantially as specified.

THO. B. WICKHAM.
